STOKER

Fred G. Julian and William M. Schweickart,
Euclid, Ohio, assignors to Pocahontas Fuel
Company Incorporated, New York, N. Y., a cor-
poration of Virginia

Application August 3, 1940, Serial No. 350,500

8 Claims. (Cl. 110—45)

This invention relates to stokers and particularly to those made for domestic and analogous uses.

The object of the invention is to provide a domestic type stoker which is simple, easy and inexpensive to make and install, which may be readily assembled in a variety of arrangements with a minimum of changes and extra parts so as to accommodate different installation conditions, which is rugged and durable, which is clean and efficient in operation and which requires a minimum of attention.

In the accompanying drawings,

Fig. 1 is a plan view of a stoker embodying the various features of this invention;

Fig. 2 is a side elevation of the stoker shown in Fig. 1;

Fig. 3 is a vertical sectional view of the burner unit taken along the axis of the conveyor;

Fig. 4 is a front elevation view of the burner unit taken transverse to the conveyor;

Fig. 5 is a vertical elevational view of the motor unit of the stoker shown in Fig. 1, taken transverse to the conveyor as indicated by the line 16—16 in Fig. 1;

Fig. 6 is a side elevational view of the motor unit taken as indicated by the lines 17—17 in Fig. 1;

Fig. 7 is an enlarged diagrammatic view of the drive unit, the figure consisting of a series of views A, B, C and D taken substantially as indicated by the lines AA, BB, CC and DD, respectively in Fig. 6, with certain details omitted or shown schematically for simplification; and

Figs. 8 and 9 are plan and elevational views of the removable cam segment for the shaker shaft driving mechanism.

Referring to Figs. 1 and 2, the complete stoker consists of a burner unit 1, an ash disposal unit 2 and a drive unit 3, as shown, in conjunction with a suitable coal supply or pick-up unit, not shown. The latter preferably consists of a coal collector unit of the type shown and described in William M. Schweickart and Fred G. Julian, Patent No. 2,306,189, issued December 22, 1942; this unit being positioned in the coal bin serving to collect coal and feed it into the bin end of the conveyor pipe 4 and is driven from the bin end of the conveyor screw 5.

Conveyor screw 5 operates within a conveyor tube or pipe 4 extending from beneath the burner unit 1 to the coal collector unit. If necessary, the conveyor 4, 5 may include a suitable knuckle, not shown, to enable the coal to be fed from a

bin which is at an angle to the portion of the conveyor 4, 5 adjacent the burner unit.

Referring now also to Figs. 4 and 5, the burner unit 1 consists of a burner body 6 fitting over the conveyor pipe 4 and clamped in position by the burner body yoke 7. The top of the pipe 4 is provided with a generally circular coal opening 8 the edges of which are engaged by the bottom of the inner annular retort surface 9 provided in burner body 6. Secured to the top of the burner body is the retort base 10, the interior annular surface 11 thereof forming an upward continuation of the retort surface 9. Positioned above and secured to retort base 10 are the tuyère segments 12 having peripheral surfaces 26, 27, openings 36, 37 and radial ribs 34.

Burner body 6 has a hollow portion 13 with a rectangular opening at one side of conveyor pipe 4 for receiving the burner end of the rectangular air tube 14. From this opening the burner body has a passageway 15 communicating with the annular air chamber 16 formed therein between the inner annular wall 9 and an outer annular wall 17, this air chamber 16 being positioned above the conveyor pipe 4. Retort base 10 is provided with an annular air passageway 18 between the inner annular wall 11 and an outer annular wall 19, this air passageway 18 communicating with the burner air chamber 16 below and the interior of the tuyère segments 12 above so that the air from the air tube 14 flows up into and around burner air chamber 16, up through air passageway 18 and into the tuyère segments 12.

The inner and outer annular walls 11 and 19, respectively, of the retort base are provided at their upper edges with flanges 20 and 21 directed toward each other. The flange 20 on the inner wall 11 is continuous throughout the circumference of the base 10.

Surrounding the burner body 6 and secured thereto is the dead ring 42 the outer edge of which has a shoulder 43 on which rests the dead plate 44 of the furnace in which the burner unit is positioned. The furnace dead plate 44 seals the furnace between the burner unit 1 and the interior furnace walls and is provided in two or more parts so that its inner edge can be positioned between the dead ring shoulder 43 and the hook end 45 on the dead ring overlying the shoulder 43.

From shoulder 43 the dead ring 42 inclines inwardly and downwardly to form an ash chamber 46 below the grates 47, and then, from about beneath the outer edge of the rotating ash table 48, the stationary dead ring 42 inclines inwardly

and upwardly substantially parallel to the outer portion of the ash table 48, with the inner edge 49 of the dead ring 42 extending vertically into a groove 50 in the ash table. There is thus formed an annular pocket 51 which maintains a seal of ashes between the rotating ash table 48 and the stationary dead ring 42.

Ash table 48 is a one-piece ring rotatably supported on the burner unit 1 by the balls 53. The inner portion of the ash table 48 is forked to provide an annular inwardly directed V-shaped groove 54 the surfaces of which engage the balls 53 above and below the centers thereof. The balls themselves are mounted in an outwardly directed V-shaped groove 55 formed at the junction of the outer annular walls 17 and 19 of the burner body 6 and retort base 10.

The outer annular wall 19 of the retort base 10 has a pocket 56 in which the top of the upper fork 57 of the ash table extends and also has a downwardly and outwardly extending projection 58 generally lying above the upper ash table fork 57. These surfaces thus cooperate to form an annular space 60 which maintains a seal of ashes between the stationary retort base 10 and the rotating ash table 48 and also to prevent the ash from leaking into the ball bearing support for the ash table. The bottom outer portion of projection 58 is formed with a plurality of ribs 59 inclined about 60° from the radius, so as to tend to feed the ash outwardly and thus further tend to prevent the leakage of ash past this seal.

The underside of the portion of the ash table 48 lying above the ash pocket 51 is formed with ribs 61 substantially tangent to the inner edge 49 of the dead ring and so directed that the ribs 61 tend to move the ashes outwardly from the pocket 51.

Supported upon the ash table 48 are the segments of the grate 47. Assembled, the grate 47 is an annular ring extending from near the bottom of the outer surface 21 of the tuyère segments 12 to just above the outer edge 43 of the dead ring 42.

The grate is provided in four sections each of which has a downwardly projecting boss 61 near each radial edge which engages the upwardly extending bosses 68 formed on the ash table 48. In addition, each grate boss 61 has a toothed lug 69 which fits under a bridge portion 70 formed in each ash table boss 68 for securing the grate segments in place. One of the toothed lugs 69 for each grate segment is shorter than the other so that the grate segment is placed in position by first fitting the long toothed lug 69 under its bridge 70 then lowering the grate segment so that the short toothed lug 69 is opposite its bridge 70 and then circumferentially moving the grate segment until the short toothed lug is under its bridge.

The underside of ash table 48 is provided with the radial teeth 12. These teeth, shown best in Figs. 5 and 6, are engaged by the tip 73 of the grate pawl 14 for rotating the ash table 48 and grate 47. The grate pawl 14 is pivotally mounted near its center upon the upper end of pawl yoke 75, the grate pawl having its end 76 opposite the tooth-engaging tip 73 weighted in order to maintain the pawl tip in engagement with the ash table teeth 12. The pawl yoke 75 is supported upon and secured to shaker shaft 77 at its burner end, where the end of the shaft is pivotally supported upon the burner body yoke 1.

During the rotation of the ash table 48 the

ash carried thereby is scraped therefrom by the stationary blade 78 provided on the dead ring 42, the blade scraping the ash into an ash discharge conduit 79 provided in the dead ring.

5 In assembling the burner unit 1 the burner body 6 is first clamped to the conveyor pipe 4 by means of the burner body yoke 1. The dead ring 42 is then secured to the burner body (if not previously secured thereto) and then the ash table 48 and balls 53 are put in place. The retort base 10 is then secured to the burner body, the tuyère segments 12 then inserted on the retort base as described, and then the grate segments 47 put in place, as described.

15 The burner body 6 may be provided with a vertical plate parallel to the conveyor pipe 4 on the side thereof opposite the air tube 14, this plate being removable and held in place by the screw 82. Plate opens into a clean out pocket 20 below the air chamber 16 to enable access thereto for removing any ash or other material which may accumulate therein. To enable a complete clean-out of the air passageways, a cleanout ring 84 may be provided in the air chamber 16, this ring having a series of spokes 85 so that upon manual rotation of the ring from the clean out pocket the otherwise inaccessible material in the air chamber 16 is brought around so that it falls into the clean out pocket. The clean out ring 84 30 is made in two pieces which are welded or otherwise secured together after the ring is positioned in place.

35 The coal flight 88 of the conveyor screw 5 for conveying the coal from the coal collector into the burner unit 1 terminates below the burner unit short of the center of the burner unit but within the outer edge of the coal output opening 8. The conveyor screw 5 is provided with a short reverse coal flight 89 commencing beyond the 40 center of the burner unit and within the coal output opening 8. The adjacent ends of the coal flight 88 and reverse coal flight 89 are substantially abrupt and are positioned oppositely about the axis of the conveyor screw.

45 The coal is thus drawn to the burner unit 1 by the coal flight 88 and then pushed up into the enclosed portion or retort 8, 11, 26 of the burner unit by the coal and reverse coal flights 50 88, 89. Some of the coal is burned within the retort while the rest of it is burned above and outside of the retort. When the coal is a coking coal, much of the coking occurs within the retort, the coke then burning above and outside of the retort. The ash resulting from the combustion sifts or is shaken through the grates 47, into the ash pocket 46, is carried by the ash table 48 around to the ash discharge conduit 79 and is there removed from the table by the scraper or blade 78.

60 The burner unit described is durable, simple in construction, and contains few expensive parts. Thus, only the tuyère segments 12 and the grate segments 47 need be made of expensive heat-resisting material, and these are such that there is a minimum of tool work upon these parts. All the remaining parts are either sufficiently air cooled or protected from the heat of the combustion as to enable them to be made of cast iron or other materials which are not only inexpensive but easy to fabricate.

65 The ashes from the burner unit 1 which are discharged through the burner unit ash discharge conduit 78 drop down into the conveyor pipe 4 through an ash input opening 100 in the top of the pipe (see Figs. 2 and 3). Preferably the

opening 100 is provided with an ash receiving member 101 clamped to the conveyor pipe 4 and having a flange 102 fitting around the sides of the ash discharge conduit 79 so as to prevent ash leakage at this point.

Within the conveyor tube 4 and beneath the ash input opening 100 the conveyor screw 5 has an ash flight 103, this flight extending from near the end of the reverse coal flight furthest from the coal output opening 8, to and under the ash disposal unit 2. Mounted on the conveyor screw 5 between the adjacent ends of the reverse coal flight 89 and the ash flight 103 is a dam 104 separating the coal and ash portions of the conveyor pipe 4. The dam 104 preferably consists of a plurality of discs of substantially the same radius as the inside surface of the coal conveyor pipe 4. These may be made in sections and welded or otherwise secured together after the flights are formed on the screw 5 or they may be mounted upon the screw shaft before the flights are formed thereon. Preferably, the conveyor dam 104 is free to rotate with respect to the shaft of the conveyor screw 5.

Referring now to Figs. 1, 2, 5 and 6, the drive unit 3 comprises a base 141 which is secured to the drive unit end of conveyor pipe 4. Secured on base 141 is a motor 142 the shaft of which drives a worm 143 and the rotating element of the fan 144. Worm 143 drives a worm gear 145 secured upon a tubular shaft 146. The right hand end of this shaft 146, as viewed in Fig. 6 rotatably supports a sprocket 147 which is releasably secured by a suitable clutch 148 to the shaft 146. This clutch 148 is operated by the knob 149.

Meshing with the sprocket 147 is the chain 150 and this in turn meshes with the sprocket 151 on jack shaft 152. Jack shaft 152 extends through the drive unit base 141 to the left of the base, as viewed in Fig. 6, where the sprocket 153 is mounted thereon. Sprocket 153 meshes with chain 154 and this in turn meshes with sprocket 155 fastened on the extension 156 of the tubular shaft portion 135 of conveyor screw 5. The base 141 has a cylindrical passageway 157 in alignment with the conveyor pipe, and the conveyor screw shaft extension 156 passes through passageway 157 and projects slightly beyond the left side of the base 141, as viewed in Fig. 6. To this left side of the base 141 is secured a bearing member 158 for the extension 156, this member also closing the passageway 157.

The motor 142 thus drives the conveyor screw 5 from the ash end thereof and the conveyor screw 5, which is in one long piece and operates in one long continuous passageway provided by the conveyor pipe, drives the coal collecting unit from the coal end thereof, rotates its coal flight 88 to convey up to the burner unit the coal delivered to the coal end of conveyor screw 5, rotates the burner end of its coal flight 88 and also the reverse coal flight 89 to force the coal up into the burner unit, rotates its ash flight 103 to convey the ash from under the burner unit over to the ash disposal unit and rotates the ash disposal unit end of its ash flight 103, and also rotates its reverse ash flight 117 and its parallel bar 118, to force the ash up into the ash can of the ash disposal unit.

The drive unit 3 drives the shaker shaft 77, and thus the ash table 48 and grate 47 of the burner unit 1, by means of a shaker shaft driving mechanism schematically shown in Fig. 7, 75

For a complete understanding of this mechanism reference should also be made to Figs. 5 and 6.

Secured to the jack shaft 152 is an eccentric 170. This eccentric operates within a spur gear 171. To this gear 171 is secured a pin 172 which extends laterally into a vertical slot 173 provided in a stationary part 174 of the drive unit (such as the base 141) so that this pin 172 prevents the spur gear 171 from rotating. Thus, as the jack shaft 152 rotates, the center 175 of the spur gear 171 moves in a substantially circular path around the axis 176 of the jack shaft 152.

Rotatably mounted upon jack shaft 152 and concentric therewith is the annular gear 177. In the structure shown there are two more teeth in the annular gear 177 than in the spur gear 171, the former having thirty-six teeth and the latter thirty-four teeth. The successive teeth of spur gear 171 mesh with the successive teeth of the annular gear 177 as the jack shaft rotates, this action being the result of the eccentric 170 and the movement which it imparts to the spur gear 171. Thus, at the end of a complete revolution of the jack shaft, and thus at the end of a complete cycle of the resulting oscillation of the spur gear 171 about a substantially circular path, the annular gear 177 is moved forward a distance corresponding to the excess of the number of teeth on the outer gear 177 over that on the inner gear 171, these excess teeth being those on the outer gear 177 not engaged by the teeth on the inner gear 171 during a complete cycle of inner gear movement. In other words, when the inner gear 171 makes a complete cycle and returns to its initial position, it causes the thirty-fourth tooth of the outer gear 177 to be in the position originally occupied by the thirty-sixth tooth on the outer gear 177, so that the outer gear 177 has moved around a distance corresponding to two teeth. The gears 171 and 177, in conjunction with eccentric 170 and pin 172, thus provide an internal epicycloidal gear train having a large gear reduction ratio.

45 The annular gear 177 is integral with the disc 178 which has the hub 179 by means of which the annular gear is rotatably supported upon the jack shaft 152. The disc 178 has integrally formed thereon one cam segment 180a and is provided with two thin radial spokes 181 on which additional cam segments 180b (see Figs. 8 and 9) may be mounted by a fastening screw passing through the aperture 182 therein and threaded into the disc 178.

55 Secured to the shaker shaft 77 at the drive unit end thereof is the cam follower arm 183 having a roller 184 pivotably supported at its outer end and positioned to engage the cam segment 180a, and such of the removable segments 180b as are in place, during the rotation of the disc 178.

65 Also secured to shaker shaft 77 is the stop arm 185 having an arcuate outer face 186. A stationary part 187 of the drive unit 3 positioned above stop arm 185 is provided with a plurality of holes into any one of which a removable stop pin 188 may be inserted with its lower end projecting into the path of the end 189 of the stop arm arcuate face 186. One end of a tension spring 190 is secured to the stop arm 185 with the other end secured to a stationary part of the drive unit. This spring tends to maintain the stop arm end 189 against the stop pin 188.

The slight rotation of annular or outer gear 177, as described, rotates disc 178 and thereby causes the cam segment 180a thereon to rotate

the cam follower arm 183 counterclockwise, as viewed in Figs. 5 and 7, against the action of spring 190. This rotation of the cam follower arm 183 correspondingly rotates the shaker shaft 77. This results in a counterclockwise rotation of pawl yoke 75 at the burner unit (see Fig. 4) so as to cause the pawl 74 to move the ash table 48 (and thus the ash grate 47) a distance corresponding to the extent to which the shaker shaft 77 is rotated.

The counterclockwise rotation of cam follower arm 183, and thus the corresponding movement of the parts driven thereby, ceases when the tip of the cam segment 180a rides under the roller 184. The spring 190 then becomes effective to return the parts toward their original position, the speed of the return being governed by the rotation of disc 178 and the rear face of cam segment 180a. The return movement of the parts ceases when the end 189 of arcuate face 186 on the stop arm 185 engages the stop pin 188.

By adjusting the position of stop pin 188 the range of movement of shaker shaft 77 may be adjusted so as to regulate the amount of rotation imparted to the ash table 48 and grate 47 for each operation or throw of the grate pawl 74. In the construction shown, the range is from zero to four teeth or notches on the ash table and grate for each pawl operation.

The frequency with which the grate pawl operates is adjustable by means of adjusting the total number of cam segments on the disc 178, this adjustment being provided by the two removable cam segments 180b.

The total amount of rotation imparted to the ash table and grate over a given period of time—conveniently termed the speed of rotation of the ash mechanism of the burner unit—is thus the aggregate of the number of notches for each grate pawl operation for as many grate pawl operations as occur during the given period of time. This speed may be varied by changing the position of the stop pin 188 (thereby changing the number of notches per grate pawl operation) or by changing the number of cam segments 180 employed (thereby changing the frequency with which the grate pawl operates).

In the construction shown the range of speed which can be imparted to the rotating ash mechanism of the burner unit is large, varying from one notch to twelve notches for one revolution of disc 178. The possible adjustments and the resulting speed are as follows:

Number of cam segments on disc 178	Position of stop pin 188	Total number of notches of rotation of ash table and grate for one revolution of disc 178
1.....	1	1
1.....	2	2
1.....	3	3
1.....	4	4
2.....	1	2
2.....	2	4
2.....	3	6
2.....	4	8
3.....	1	2
3.....	2	4
3.....	3	6
3.....	4	12

As a result of this construction the uniform rotary motion of the stoker motor is transformed to an intermittent rotary motion of the ash mechanism of the burner unit with the speed

of rotation of the ash mechanism very much less than the motor speed, while affording by simple means an adjustment of the ash mechanism speed over a very substantial range compared to the median speed of the ash mechanism. By this control of the speed of the ash mechanism of the burner unit, the stoker installation may readily be initially adjusted to the speed best suited to the installation, and then the user may readily vary this speed over a substantial range in accordance with weather or other conditions related to the action of the fire. This control thereby enables the stoker to be operated at high efficiency and to produce a minimum of unburned fuel in the ash. For example, the user, by adjustment of the stop pin, may increase the normal speed of the ash mechanism during the severe winter months and decrease its speed during the summer months (at which time the only function of the stoker is to supply hot water).

It is to be noted that the adjustment of the stop pin 188 may be made at any time, for the stop pin will drop down into place to engage the end 189 of stop arm 185 after the arcuate face 186 of the stop arm has moved out from under the bottom of the stop pin. Thus, with the parts as shown in Fig. 7, and assuming the stop pin is moved from position 4 to position 2, the ensuing operation of the grate pawl is four notches, but during this operation the face 186 moves from under stop pin 188 so that the stop pin falls to its lowermost position. As a consequence, the end 189 of the stop arm is stopped on its return in the two-notch position so that all further grate pawl operations will each be two notches.

The stoker described is particularly flexible in the manner in which it can be assembled to provide different arrangements suitable to different installation conditions.

We claim:

1. A stoker having a continuous passageway and a single conveyor screw operating therein, said screw having a coal flight for conveying coal in one portion of the passageway toward and up into the stoker burner and having an ash flight for conveying ash in another portion of the passageway from the burner unit toward an ash receptacle, the burner of said stoker having a rotating ash mechanism, means connecting the stoker motor with the ash end of said screw beyond the end of the ash flight for rotating the screw, and means directly connecting the stoker motor with the rotating ash mechanism on the burner so that the drive for the ash mechanism does not include the conveyor screw.

2. A stoker as set forth in claim 1 in which the means connecting the stoker motor with the rotating ash mechanism comprises a shaker shaft, gearing connecting said shaft to said motor and acting to oscillate said shaft, means at the other end of said shaft acting to rotate said ash mechanism from said shaft, and adjustable means regulating the amount of rotation of the ash mechanism for each oscillation of the shaft.

3. In a stoker mechanism a retort having an upper portion with a vertical passage for the coal and a lower separable portion, a feed tube of substantially constant diameter passing between said portions of the retort and having an orifice intermediate its ends and positioned to open upward into the vertical passage of the retort, means for clamping said upper and lower portions of the retort around said tube rigidly to fasten the parts together and means within the tube for feeding coal horizontally to said orifice and upward

therethrough into the vertical passage of the retort.

4. In a stoker mechanism a retort having an upper portion with a vertical passage for the coal and a lower separable portion and an ash ring surrounding the upper portion of the retort and having a downwardly directed outlet for the ashes, a feed tube of substantially constant diameter passing between said portions of the retort and having a plurality of orifices located intermediate its ends and positioned to open upward, one orifice leading to the vertical passage of the retort and the other orifice receiving the discharge of ashes from said outlet, means for clamping said upper and lower portions of the retort around said tube to rigidly fasten the parts together, and means within the tube for feeding coal horizontally to the orifice leading upward to the retort and upward through said orifice into the vertical passage of the retort and simultaneously feeding ashes horizontally received through the orifice at the said ash outlet.

5. Stoker mechanism as set forth in claim 4 in which the feed tube has a third orifice located between the ends of the tube and opening upward for the discharge of ashes and the ash feed means within the tube has an end portion lifting the ashes upward through said third orifice.

6. Stoker mechanism as set forth in claim 4 in

which the feed tube has a third orifice located between its ends and opening upward for the discharge of ashes fed from said ash outlet and the feed means within the tube comprises a continuous unitary structure having a helical blading for feeding the coal and ashes and a bar member between portions of said helical blading for forcing ashes up through said third orifice.

7. In a stoker a drive unit comprising a motor, 10 blower and gearing driven by said motor, a combined ash and coal screw conveyor driven from said gearing, a continuous straight ash and coal tube section connected at one end to said drive unit and housing said ash and coal screw, a burner unit including a retort member mounted on an intermediate portion of said ash and coal tube and receiving coal from said coal screw and having a grate means delivering ashes to said ash screw, an ash disposal unit on said ash and coal tube between said drive unit and said burner unit and receiving ashes from said ash screw, and an air tube connecting said blower with the retort member of said burner unit.

8. A stoker combination as set forth in claim 25 7 in which the burner unit has a rotary part connected by a shaft to be driven from the gearing of the drive unit.

FRED G. JULYAN.

WILLIAM M. SCHWEICKART.
